JOSEPH W. HEETER, OF BUTLER, PENNSYLVANIA.

OIL SAVER FOR OIL WELLS AND PACKING SCREWS THEREFOR.

Application filed August 15, 1924. Serial No. 732,184.

The present invention relates broadly to oil savers adapted to be operatively applied to a casing head during the drilling operation, and more particularly to an improved screw for compressing the packing into cooperative relation to the drilling line or cable.

It is customary in the art to which the present invention relates to provide oil savers comprising openable sections adapted to receive therebetween a body of packing material which may be compressed to any desired extent into engagement with the line wire or cable carrying the drilling tools. In order to permit easy application and removal of such savers, the screws utilized for compressing the packing have necessarily been constructed in sections adapted to be separated, placed in position around a cable, and then moved into assembled relationship. In order to permit the cable to work freely through the central opening extending through such screws, the openings have necessarily been of considerably greater diameter than the maximum diameter of the line wire or cable being utilized. This cable, therefore, has not been effective for properly aligning the sections of the screws, with the result that considerable difficulty is frequently encountered in properly assembling the same and threading them into the base of the oil saver. Attempts have been made to overcome this difficulty by applying dowel pins to the operating handles of one section and corresponding openings to the other section. Due to the difference in diameter before referred to, however, and the comparatively great weight of the screw sections, considerable difficulty has frequently been experienced in bringing the dowel pins into registration with the openings.

It is one of the objects of the present invention to provide an oil saver having a sectional screw of such construction that the sections thereof may more readily be brought into proper cooperative relationship.

In the accompanying drawings, there is shown for purposes of illustration only, a preferred embodiment of the present invention, it being understood that the drawings do not define the limits of my invention, as changes in the construction and operation disclosed therein may be made without departing from the spirit of the invention or scope of my broader claim.

In the drawings:

Figure 1 is a vertical sectional view through a portion of a casing head illustrating my improved oil saver in position thereon;

Figure 2 is a transverse sectional view on the line II-II of Figure 1, looking in the direction of the arrows; and

Figure 3 is a detail view on an enlarged scale of a portion of one of the packing screw sections.

In carrying out the present invention, there may be provided an oil saver comprising a base 2 adapted to be inserted into position within a cap shaped depression 3 formed on the casing head 4 of a standard casing 5.

The base may be held in cooperative relation to the casing head by set screws 6 extending through the head and engaging the inclined upper surface of the base.

In order to permit the oil saver to be readily applied to a cable, it is desirable that it should be of sectional construction, permitting it to be slipped around the cable at any point intermediate the ends thereof. For this reason, the saver may conveniently comprise sections 7 and 8 having a pivotal connection 9 and a clamping means 10 for holding the sections in closed position. These sections are adapted to form a packing receiving recess for packing 11, which is usually formed of rubber, having a longitudinally extending slit through one side thereof to permit the same to be slipped around the line wire or drilling cable C.

At such times during the drilling operation as there is no flow of oil, there is obviously no need for maintaining the packing 11 in engagement with the cable, as it not only increases the friction which must be overcome in operating the cable but also results in undue wear of the packing. At other times,

however, as for example when oil is flowing, it is desirable to have the packing engage the cable sufficiently tightly to prevent the escape of oil through the oil saver. This compression of the packing may be accomplished by a packing screw comprising separable sections 13 and 14 adapted when assembled to be threaded into the split threaded opening 15 formed by the oil saver sections 7 and 8. Preferably a split or hinged washer 16 will be provided between the packing and the packing screw for transmitting the desired pressure from the screw to the packing.

Savers of the character contemplated by

the present invention are of considerable size and, being constructed almost entirely of iron or steel, have a weight such that handling thereof presents a considerable problem. The 5 packing screws themselves frequently weigh a great many pounds, thereby making it essential in order to permit their ready assembly and threading into the oil saver to provide means insuring proper assembly and registration of the sections. For this purpose I provide one of the sections, herein illustrated as the section 14, with a circular boss 17 projecting from the inner face thereof, and provide the other section with a circular recess 18 adapted to receive this boss. Preferably 10 this registering means for the sections will be located thereon intermediate the ends of the threaded sections whereby the center thereof substantially coincides with the center of a triangle joining the ends of the threaded sections of the screw sections and the ends of the handle portions 19 thereof. Due 15 to this construction, the sections may initially be brought into assembled relationship with their longitudinal axes extending at an angle to each other, as indicated by chain lines in Figure 3, and thereafter brought into proper registration by grasping the handle portions to cause the boss 17 to rotate in the recess 18. 20 25 30 In actual practice it has been found that this

construction materially lessens the time required to effect the proper assembling of the sections with the screw threaded portions of the different sections occupying such relationship that the screw as a unit may be 35 threaded into the oil saver into operative relation to the washer 16. It will be apparent that in the event of the commencement of oil flow before the application of the oil saver, this saving in time represents a material saving in oil as well as labor. 40

The advantages of the present invention arise from the provision of an oil saver having a packing screw constructed with registering means adapted to facilitate proper assembly and registration of the sections. 45

I claim:

A clamping screw, comprising a pair of separable sections one of which is provided with a substantially circular boss having an 50 opening therethrough for the reception of a cable, the other section having a substantially circular recess therein for reception of the boss whereby the two sections may be fitted together about a cable, the boss and recess being adapted to permit relative rotation thereof into alignment. 55

In testimony whereof I have hereunto set my hand.

JOSEPH W. HEETER.
